CLAIM

I claim the ornamental design for the quick opening sillcock, as shown and described.

DESCRIPTION

FIG. 1 is a perspective view of my new quick opening sillcock;

FIG. 2 is a front view thereof;

FIG. 3 is rear view thereof;

FIG. 4 is a side view thereof from one side;

FIG. 5 is a side view thereof from the other side;

FIG. 6 is a top view thereof; and

FIG. 7 is bottom view thereof.

FIG. 8 is a rear view of an alternate embodiment of my new quick opening sillcock;

FIG. 9 is a side view thereof from one side;

FIG. 10 is a side view thereof from the other side;

FIG. 11 is a top view thereof; and,

FIG. 12 is a bottom view thereof.

The perspective view of said alternate embodiment is the same as FIG. 1 and the front view of said alternate embodiment is the same as FIG. 2.
